UNITED STATES PATENT OFFICE.

GEORGE M. PORTEOUS AND FREDERICK S. MILLER, OF CHICAGO, ILLINOIS.

DESIGN FOR A PHOTOGRAPH-EXHIBITOR STAND.

SPECIFICATION forming part of Design No. 18,872, dated January 15, 1889.

Application filed December 17, 1888. Serial No. 293,888. Term of patent 7 years.

To all whom it may concern:

Be it known that we, GEORGE M. PORTEOUS, a citizen of the United States, and FREDERICK S. MILLER, a subject of the Queen of Great Britain, both residing at Chicago, in the county of Cook and State of Illinois, have invented and produced a new and original Design for a Photograph-Exhibitor Stand, of which the following is a specification, reference being had to the accompanying drawing, forming part thereof.

The drawing represents in elevation a photograph-exhibitor stand embodying our design.

15 The leading feature of our design consists in the stand having a pair of upwardly-extending curved arms provided with ornamental scrolls, substantially as shown in the drawing, and hereinafter more particularly described.

In said drawing, A represents a photograph-exhibitor stand having at its upper portion a pair of upwardly-extending curved arms, a

and a, which said arms substantially meet at their lower ends and from such point of meeting diverge upwardly. Each arm has a gradual and symmetrical curvature, and is ornamented by representation of scroll-work a', thereby giving a highly-pleasing effect to the whole and avoiding the barren effect or scant appearance which would be involved were the curved arms destitute of such ornamental scrolls. The portion of the stand below its said ornamented curved arms can be either plain or ornamented, as may be desired. 35

What we claim is—

In a design for a photograph-exhibitor stand, the pair of upwardly-extending curved arms a, provided with ornamental scrolls a', substantially as shown and described.

GEORGE M. PORTEOUS.
FREDERICK S. MILLER.
